(57) **CLAIM**

The ornamental design for an antenna assembly, as shown and described.

DESCRIPTION

FIG. 1 is an isometric view of an antenna assembly showing the design;

FIG. 2 is a back elevation view thereof;

FIG. 3 is a left side elevation view thereof, the right side being a mirror image thereof;

FIG. 4 is a plan view of the design;

FIG. 5 is a front elevation view of the design;

FIG. 6 is a right side elevation view thereof, the left side being a mirror image thereof; and,

FIG. 7 is a bottom view of the design.

The portions of the antenna assembly shown in broken lines form no part of the claimed design.
